DESIGN FOR A LAWN MOWER OR THE LIKE

Allyn R. Cooper, Marshalltown, Iowa, assignor to Cooper Manufacturing Company, Marshalltown, Iowa, a corporation of Iowa

Application August 1, 1944, Serial No. 114,676

Term of patent 14 years

(Cl. D40--1)

To all whom it may concern:

Be it known that I, Allyn R. Cooper, a citizen of the United States and a resident of Marshalltown, in the county of Marshall and State of Iowa, have invented a new, original, and ornamental Design for a Lawn Mower or the Like, of which the following is a specification, reference being had to the accompanying drawing, forming a part thereof.

Figure 1 is a front perspective view of a lawn mower, showing my new design; and Figure 2 is a rear perspective view thereof, a portion of the handle being broken away for convenience of illustration.

I claim:

The ornamental design for a lawn mower or the like, substantially as shown.

ALLYN R. COOPER.
